No. 11,441

September 30, 1879

UNITED STATES PATENT OFFICE.

LE ROY W. FAIRCHILD, OF NEW YORK, N. Y.

DESIGN FOR PENCIL-CASES.

Specification forming part of Design No. **11,441**, dated September 30, 1879; application filed September 6, 1879.
[Term of patent 7 years.]

To all whom it may concern:

Be it known that I, LE ROY W. FAIRCHILD, of the city, county, and State of New York, have produced a new and original Design for a Case for Small Implements, such as a pencil, nail-cleaner, or button-hook, of which the following is a full, clear, and exact description, reference being had to the accompanying engraved illustration, making a part of this specification.

My invention belongs to that class of ornamental cases which are known to the trade as "watch-charms."

A represents the entire design. b is a ring. c is the eye in which the ring b is loosely held. d is the figure of a snake wrought in relief

upon the shell of the case, which it encircles in a spiral coil extending nearly or quite through the space from bead e to bead f.

The various parts shown in the illustration may be wrought in different colors, or different shades of the same color, if desired.

What I claim as my invention is—

A design for a small-implement case, consisting of the figure of a snake, d, in relief, encircling the outer shell of the case, the ring b, and the eye c, substantially as shown and described.

LE ROY W. FAIRCHILD.
